UNITED STATES PATENT OFFICE.

LEO GESCHICKTER, OF WASHINGTON, DISTRICT OF COLUMBIA, ASSIGNOR TO THE INFALLIBLE MOTH AND DUST PROOF RECEPTACLE COMPANY, OF WASHINGTON, DISTRICT OF COLUMBIA.

MOTHPROOF BAG AND GARMENT-SUPPORTING DEVICE THEREFOR.

1,082,858.

Specification of Letters Patent.

Patented Dec. 30, 1913.

Application filed December 13, 1912. Serial No. 736,589.

To all whom it may concern:

Be it known that I, LEO GESCHICKTER, a subject of the Czar of Russia, residing at Washington, in the District of Columbia, have invented certain new and useful Improvements in Mothproof Bags and Garment-Supporting Devices Therefor; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in moth-proof bags and means therein for supporting garments independent of the bag, and comprises a receptacle or bag in which a removable rack or frame is mounted and which may be removed when it is desired to fold the bag into a compact form.

The invention comprises various details of construction and combinations and arrangements of parts which will be herein-after fully described, shown in the accompanying drawings and then specifically defined in the appended claims.

I illustrate my invention in the accompanying drawings, in which:—

Figure 1 is a perspective view of a portion of a bag or receptacle, a portion of the top of the bag being broken away to better illustrate the invention. Fig. 2 is a detail view of a rack forming a part of the invention. Fig. 3 is a plan view of the top of the bag or receptacle, showing eyelets mounted at one side of the transverse center of the top, and Fig. 4 is a sectional view longitudinally through the upper end of the bag with the rack adjusted in place therein.

Reference now being had to the details of the drawings by letter, A designates a bag of any suitable shape and material, such as canvas, and which may be treated chemically or otherwise in order to render the same more effectual in resisting the attacks of vermin and which may be water or weather proof. The bag shown is preferably rectangular in cross section and is closed at its top and which latter is provided with eyelets B mounted in reinforcing strips C which are positioned at one side of the trans-

verse center of the bag in order to allow the same to fold along the central line without interference from said eyelets. A rack, designated by letter D, of general rectangular shape to conform to the shape of the bag, is mounted in the closed upper end of the bag, and screws F pass through said eyelets and holes d formed in the cross-pieces D' of the rack and engage the socket members E which are countersunk in the under faces of said cross-pieces. A bail-shaped suspending handle K has shank portions bent at right angles at K', and eyes K² at their ends through which said screws pass. Upon reference to Fig. 4 of the drawings, it will be noted that, when the handle is adjusted in place, the vertical portion thereof will come along the center of the bag in order to allow the same to hang perfectly plumb and, by which provision, the eyelet being at one side of the center along the folding line will not interfere with the bag when folded to compact form for storage or shipment. A bail N is fastened to the under surface of the rack and forms means upon which the garments may be held.

Any suitable means for holding the opening to the bag closed to form a tight joint may be employed, such as strips O which clamp the flaps R upon opposite edges of the opening and which strips are held together by screws T passing through registering apertures S and adapted to engage a socket member, not shown, similar to the member E illustrated in Fig. 4.

By the provision of a moth-proof bag and garment supporting device therefor as shown and described, it will be noted that, when the bag or receptacle is adjusted for use, the rack will tend to hold the bag distended and the weight of the garments contained within the bag or receptacle is thrown entirely upon the rack, thus relieving the bag of any strain incident to the weight of garments. The eyelets through which the screws pass for fastening the supporting handle being at one side of the center line of the top will allow the bag to fold without interference from said eyelets after the rack and handle has been removed, thus allowing the bag to be folded into a compact form.

What I claim to be new is:—

1. A collapsible moth-proof bag and gar-

2

ment supporting device therefor comprising, in combination with a bag having closed upper end and suitable opening in the body portion thereof, a rack having cross-pieces 5 and mounted in the top of the bag above the upper edge of the opening therein, a bail-shaped member having arms which are bent at right angles and each terminating in an eye, screws passing through said eyes, 10 the top of the bag and engaging said cross-pieces, the bail-shaped portion of said member being positioned opposite the longitudinal centers of said cross-pieces, as set forth.

2. A collapsible moth-proof bag substantially rectangular in cross section and having its upper end permanently closed with an opening in one corner terminating at its upper end a short distance from the upper end of the bag, a rack mounted within the 15 upper closed end of the bag and holding the same extended its width, flaps projecting from the marginal edges of the opening, clamping means for holding said flaps in contact with each other to form a tight joint,

and means fastened to the top of the bag and 25 rack for supporting the bag, as set forth.

3. A collapsible moth-proof bag and garment supporting device therefor comprising, in combination with the bag with closed upper end and a suitable opening in the 30 body portion thereof, a garment supporting rack within the upper portion of the bag, eyelets formed in the top of the bag at one side of the transverse center thereof, reinforcing strips about said eyelets, a bail-shaped member having angled shank portions and eyes at the ends thereof, screws 35 passing through said eyes and top of the bag, and socket members seated in said rack and engaged by the inner ends of said 40 screws, as set forth.

In testimony whereof I hereunto affix my signature in the presence of two witnesses.

LEO GESCHICKTER.
